UNITED STATES PATENT OFFICE.

FRANK O. GREEN, OF DES MOINES, IOWA.

DESIGN FOR A FURNACE.

No. 39,608.

Specification for Design.

Patented Oct. 6, 1908.

Application filed May 14, 1907. Serial No. 373,670. Term of patent 7 years.

To all whom it may concern:

Be it known that I, FRANK O. GREEN, a citizen of the United States, residing at Des Moines, in the county of Polk and State of Iowa, have invented a new, original, and ornamental Design for Furnaces, of which the following is a specification, reference being had to the accompanying drawing, forming part thereof.

The figure is a perspective view of a furnace, showing my new design.

Referring to the drawing it will be observed that the essential features of my design comprise the base 10 and the dome portion 11 connected by the intermediate fluted portion 12 flaring upwardly from the base to the dome. From the dome extends a portion 13 provided with a front plate 14 of approximate inverted keystone shape and provided with a fuel door 15 the lines of which

are approximately parallel with those of the front plate. The base 10 is also provided with a face plate 16 similar in configuration to the face plate 14, and of such dimensions that the side lines thereof appear to be in continuation of the corresponding lines of said plate 14. The plate 16 is also provided with a door 17 the lines of which conform to the configuration thereof. In the rear of the furnace body is a cylindrical element 18, and at the bottom of the furnace is the circular plate 19.

I claim.

The ornamental design for a furnace, as shown and described.

FRANK O. GREEN.
